COMBINED TOTE BAG AND STADIUM SEAT CUSHION OR SIMILAR ARTICLE

Opal I. McKinney, R.R. 4, Grayson, Ky. 41143

Filed Jan. 17, 1973, Ser. No. 324,438

Term of patent 14 years

Int. Cl. D6—09

U.S. Cl. D6—202

FIG. 2

FIG. 1

FIG. 3

FIG. 4

FIG. 1 is a front elevational view of a combined tote bag and stadium seat cushion or similar article showing my new design;

FIG. 2 is a rear perspective view;

FIG. 3 is a right side elevational view; and

FIG. 4 is a bottom plan view.

I claim:

The ornamental design for a combined tote bag and stadium seat cushion or similar article, substantially as shown and described.
